UNITED STATES PATENT OFFICE.

HENRY MESSEY, OF ROXBURY, MASSACHUSETTS.

IMPROVEMENT IN AIR-ENGINES.

Specification forming part of Letters Patent No. 37,299, dated January 6, 1863.

To all whom it may concern:

Be it known that I, HENRY MESSEY, of Roxbury, in the county of Norfolk and State of Massachusetts, have invented a new and useful Improvement in Air or Caloric Engines; and I do hereby declare that the following is a full, clear, and exact description of the same, reference being had to the accompanying drawings, forming a part of this specification, in which—

Figure 1 is a vertical section of an engine with my improvements. Fig. 2 is a plan of the same, partly in section. Fig. 3 is a front view of the interior of the chest which contains the induction and eduction valves of the working-cylinder.

Similar letters of reference indicate corresponding parts in the several figures.

This invention consists, first, in the attachment of the pump-cylinder of an air-engine to the working-piston and the employment of a stationary compressing-piston, the object being to employ the weight of the said cylinder to aid the working-piston in its downward or return stroke, the engine being single-acting and the air only operating to produce the upward stroke.

It also consists in a certain arrangement of the induction and eduction valves and valve-chest of the working-cylinder of the engine, whereby great facility is afforded for getting at the valves whenever necessary.

To enable others skilled in the art to make and use my invention, I will proceed to describe its construction and operation.

A is the working-cylinder, arranged in an upright position, and having its lower part sunk in and surrounded by an air-heating chamber, B, which also surrounds and encloses the furnace C. This cylinder is open at the top.

D is the working-piston, fitted to the cylinder A with suitable packing, and having secured to its upper side and concentric with it the pump-cylinder P. The piston D is made hollow, and the cavity a in its interior has free communication with the interior of the pump-cylinder P, provided by openings s s, shown in Fig. 1, and the said piston is provided with a valve, e, at the top opening downward and inward from the atmosphere to its cavity a.

E is the pump-piston, having for its piston-rod a portion of a pipe, F, which is connected

with the air-heating chamber B, to supply air thereto, the said pipe being fitted to the tight cover P' of the pump-cylinder with a stuffing-box, G. The said cover P' is furnished with a valve, b, opening downward or inward from the atmosphere. The stationary pump-piston E is hollow, and its internal cavity is always in communication with the pipe F; and the said piston has a valve, c, in its top opening downward and inward, and a valve, d, in its bottom opening upward and inward.

H is the valve-chest, containing the induction-valve I for the induction of the compressed and heated air from the furnace C into the lower part of the working-cylinder A, and the eduction-valve J, for the escape of the exhausted air from the said cylinder to the atmosphere. The air from the furnace is conducted to the valve-chest by a pipe, M, and the exhausted air leaves the valve-chest by a pipe, J.

The valves I J may be operated by any suitable mechanism of substantially similar character to what is employed for working the induction and eduction valves of steam-engines.

By the attachment of the pump-cylinder to the working-piston the weight of said cylinder is made to assist in producing the downward stroke of the said piston, and by that means I succeed in obtaining in air-engines—more especially in those having a single cylinder—a more uniform development of power throughout the whole revolution of the shaft than can otherwise be obtained. The operation of the two pistons and the several valves, applied in connection with them in such combination of the pumping-cylinder and working-piston, is as follows: In the downward movement of the working-piston D the valves b and d are closed, and c and e are open, and the air with which the part of the pump-cylinder above its piston E has been previously filled is compressed and forced through the valve e, pump-piston E, and pipe F into the chamber B, and thence through the openings m m into the furnace C, while the pump-cylinder is filled below the piston with fresh air, entering through the valve e. In the upward movement of the working-piston D, produced by the expansion of heated air admitted to the cylinder A from the furnace through the pipe M and valve I, the valves b and d are open and c and e closed, as represented in Fig.

1, and the air with which the pump-cylinder E has been filled below its piston P is forced through the valve *d*, piston E, and pipe F into the chamber B and furnace C, while fresh air enters the pump-cylinder E above its piston P through the valve *b*. The pump is thus double-acting, operating both in the upward and downward stroke of the working-piston D, which may be caused to produce a rotary movement of the crank-shaft L of the engine by any suitable system of connections. Fig. 1 represents the connection with the crank as being made by a forked rocking beam, N, and rods O V.

The arrangement of the valve-chest H and valves I J to afford convenience for getting at the valves is illustrated in Figs. 2 and 3. The valves are of the puppet kind, and the chest is divided into four compartments, *i i' j j'*, the compartment *i* having the induction-pipe M attached and being always in communication with the furnace or air-heating chamber, the compartment *j* having the exhaust-pipe J attached, and the two lower compartments, *i'* and *j'*, both communicating with the cylinder. The induction-valve I is placed between the compartments *i* and *i'*, and the eduction-valve J between the compartments *j* and *j'*. The closet H is situated opposite to an opening, *r*, provided in the cylinder-casing or air-heating chamber B of the engine, such opening being fitted with a tight cover, *t*, which is only re-

moved when it is desired to examine, adjust, or repair the valves. The chest is also constructed with an open front fitted with a light movable cover, *u*, such cover being opposite to the opening *r*. By taking off the two covers *t* and *u* the whole of the interior of the valve-chest is exposed to view, as shown in Fig. 3, and the valves can be examined, adjusted, or taken out without difficulty.

Instead of having the air circulate around the fire-box, it may be prevented from circulating over the sides thereof by filling the space between it and the outer casing with plaster-of-paris or other non-conducting material.

What I claim as my invention, and desire to secure by Letters Patent, is—

1. The combination, with a stationary pump-piston, of a pump-cylinder attached to and having a reciprocating movement corresponding with the working-piston, substantially as and for the purpose herein specified.

2. The arrangement of the valve-chest H, valves I J and the movable front plate, *u*, of the chest, whereby provision is made for getting at the valves, substantially as herein described.

HENRY MESSER.
